(57) **CLAIM**

The ornamental design of a winch handle, as shown and described.

DESCRIPTION

FIG. 1 is a top, front and left perspective view of a winch handle showing our new design;

FIG. 2 is another perspective view of the handle thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines showing a winch body and winch handle grip in FIG. 1 are included for the purpose of illustrating environment and form no part of the claimed design.
